UNITED STATES PATENT OFFICE.

LEO PLATT, OF NEW YORK, N. Y.

GARTER AND METHOD OF MAKING SAME

1,410,533.

Specification of Letters Patent. Patented Mar. 21, 1922.

Application filed September 24, 1921. Serial No. 502,924.

To all whom it may concern:

Be it known that I, LEO PLATT, a citizen of the United States of America, residing at New York, in the county of New York and State of New York, have invented certain new and useful Improvements in Garters and Methods of Making Same, of which the following is a specification.

This invention relates to garters and the like and to a method of making same.

An object of the invention is to provide a garter ribbon of attractive appearance which can be easily and quickly made up into garters and the like.

Other and further objects and advantages of the invention will be in part described and in part obvious as the specification is proceeded with.

In the accompanying drawings forming part of this specification:

Figure 1 is a completely made garter.

Figure 2 is a perspective view of a bolt of ribbon showing a length thereof being severed from the bolt;

Figure 3 is a transverse sectional view through the ribbon.

In making garters it has been customary to gather the ribbon before sewing to the garter elastic, after which a ribbon or fabric facing is secured to the back of the elastic by sewing. Garters have also been made by sewing two pieces of ribbon together along their side edges and then drawing or inserting an elastic therebetween. These methods are rather burdensome, and according to the present invention are much simplified.

Referring more particularly to the drawings, 5 denotes a woven ribbon comprising a central tubular portion 6 of suitable width to accommodate any desired width of garter elastic 7. As best illustrated in Figure 3, the marginal side portions or extensions 8 are solid for a purpose presently to be described.

In making the ribbon 5 the tubular portion 6 and marginal side portions or extensions 8 are woven in a single operation, that

is the ribbon is turned out complete by the loom. The ribbon is then rolled, into bolts from which lengths suitable for making garters and the like may be severed.

In making up a garter from the ribbon 5, a section thereof is severed, and after a piece of garter elastic somewhat less in length than that of the ribbon section has been inserted in the tubular central portion 6 of the ribbon, the latter is gathered preparatory to sewing the ends of the ribbon and the ends of the elastic together, the lines of stitching being indicated at 9.

The solid marginal side portions or extensions not only add to the attractiveness of the ribbon and the completed article into which the ribbon is made, but they assure a much more secure connection at the point 9. These marginal side portions, in addition to the advantages above set forth obviate the necessity of sewing on the customary ruffle or flounce with which ladies' garters are provided.

While I have shown the marginal side portions 8 of equal width, it will be understood that they may be of different widths.

What I claim is:

1. A method of making garters comprising weaving a strip with a central tubular body portion and a solid marginal edge, then inserting an elastic webbing in said tubular portion of less length than said strip and then securing the ends of said elastic webbing together.

2. A method of making garters comprising weaving a strip with a central tubular body portion and a solid marginal edge, and cutting said strip into lengths suitable for garters, then inserting an elastic webbing in said tubular portion of less length than said severed strips and then sewing the ends of said severed strip and the ends of said elastic webbing to each other and together.

In testimony whereof I affix my signature.

LEO PLATT.
